Theodore T. Strong & Marcus T. Moody
Gillies Patent

75

The Schedule referred to in this Gillies Patent and making part of the same containing a description in the words of the said Theodore T. Strong & Marcus T. Moody themselves of their improvement in the Machine for hulling, cleaning & polishing Rice, Barley, Broom, Corn & other small seeds.

To all persons to whom these presents shall come, We Theodore T. Strong house joiner & Marcus T. Moody Cabinet Maker both of Northampton in the County of Hampshire in Commonwealth of Massachusetts send greeting. Be it known that we the said Theodore T. Strong and Marcus T. Moody have invented constructed made and applied to use a new & useful improvement for the purpose of cleaning threshing & polishing of Rice, Barley, Broom corn & other small seeds having a hard kernel and which are difficult of separation from the hull or husk called by them Strong & Moody's improved Patent Huller, Smutter & polisher specified in the words following to wit. This improvement consists in a firm quadrangular frame of any required dimensions. In this frame is to be placed a perpendicular shaft, moving in a horizontal direction. On the shaft is to be fixed a truncated cone of any required dimensions the circumference or exterior surface of which is to be studded clothed or charged with strong and teeth, pins or points of metallic wire set in brads or any other firm & elastic substance. Surrounding this truncated cone so studded charged & clothed & exactly corresponding with its exterior surface is to be placed a hollow cylinder the interior surface of which is

NOV. 17, 1832

to be clothed studded or charged in the same manner & with the same materials as the truncated cone above mentioned. Beneath the truncated cone and cylinder aforesaid are to be placed a winnowing screen on the same or another upright shaft is to be affixed another truncated cone similar to the one first herein mentioned & having a corresponding hollow cylinder.

The exterior surface of the cone and the interior surface of the cylinder last mentioned are to be studded clothed & charged with very firm and stiff bristles or hair or with the skin of the dog fish having an underlay of caoutchouc or other elastic substance. Beneath this last mentioned cone & cylinder are to be placed a winnowing screen & beneath them a bolt covered with screen wire.

Method of operation. The seeds to be cleaned, hullled or polished are first to be passed thru' a pair of common mill stones or similar stones having the upper stone hung on a stiff, hair & raised so high as only to crack & partially separate the outer coat or hull of the seeds. After running the seed as it comes from the mill stones it is to be passed by a hopper between the truncated cone & its corresponding hollow cylinder which are studded with pins or points of metallic wire. when the seed will be entirely divested of the hull or hulls & are then to be passed thru' the winnowing screen beneath. If a more perfect polish is required the seeds are then to be passed thru' the second cone & its corresponding cylinder from which they are passed into the winnowing screen beneath & from the screen into the bolt covered with screen wire. The said Moody and Strong claim as their joint invention in the improvement herein specified & described the method of hulling, cleaning & polishing or winnowing of rice.

Barley, Wheat, corn and other small grains having a hard kernel difficult to separate from the hull or hulls by means of truncated cones revolving on a perpendicular shaft in a hollow cylinder & clothed with and ^{tusks} points of metallic wire set in leather or any other strong & elastic substance. & also for truncated cones revolving on a perpendicular shaft & in a hollow cylinder having the cones & cylinder clothed charged or studded with stiff, bristles or hair or with elastic grano or India rubber. as an under lay over which are placed a coating of the skin of the dog-fish as polished or burnished as herein specified & described & their claim on this invention, as as an improvement on "Strong and Morley's huller smutter & polisher" secured to the present applicants by letters patent from the U. S. States dated Augst 29th 1832. Be testimony that the above is a true specification of our said improvement as above described we have hereunto set our hands the 24th day of September in the year of our Lord 1832
